SUCCESSIVE ANTENNA SELECTOR

Harold O. Peterson, Riverhead, N. Y., assignor to
Radio Corporation of America, a corporation of
Delaware

Application November 16, 1928, Serial No. 319,939
Renewed April 12, 1933

30 Claims. (Cl. 250—20)

This invention relates to the reception of radio signals, and more particularly to antenna selection for diversity receivers for the reduction of fading of high frequency signals.

Communication on very high frequency carriers is economical of power, but is handicapped by the prevalence of fading. Inasmuch as fading may differ very widely at geographically spaced points, or in different planes of polarization, it has been proposed to reduce its effect by diversity systems of reception characterized by the use of a number of antennas having different fading characteristics. Because the phase of the radio frequency energy at the different points of collection may fluctuate considerably it is not feasible to combine the received energies directly together. One suggestion to overcome this difficulty is to switch rapidly from one antenna to another in the series, but this scheme suffers from the disadvantage that the antenna at which fading is not prevalent is coupled to the receiver only intermittently. Another and valuable method is to combine the received energies after rectification but this is not perfect because the volume of the received energy is apt to vary between the extremes of almost complete fading on all of the antennas, to a total absence of fading on any of the antennas.

To overcome this disadvantage is one object of my invention, which I accomplish by a method which includes collecting signal energy on a plurality of antennas, and feeding the collected energy to a receiver from only so many of the antennas as may be necessary to keep the energy supplied to the receiver at a predetermined desirable value. From one aspect the invention may be considered to be a volume control in which the adjustment of the volume is attained by connecting a variable number of antennas of any type or spacing to a receiver. From another aspect the invention may be considered as a diversity factor receiving arrangement in which antennas having relatively different fading characteristics are successively coupled to a receiver until an antenna at which fading is not prevalent is reached. This result is accomplished by employing separate amplifiers with the antennas, combining the outputs from the amplifiers, and controlling the gain in the amplifiers at graduated amounts from a common volume control responsive to the volume of the combined energy, so that more of the amplifiers are made conductive as the volume of the combined energy is decreased.

This system has two further advantages in at

least partially overcoming two difficulties which will next be described. In order to control the volume of the combined output from the diversity antennas it has been proposed to equip each of the amplifiers for each of the antennas with a volume control, but this, in addition to requiring a considerable number of volume controls, suffers from a much greater disadvantage in that the amplifiers of those antennas at which fading is prevalent are given increased gain, in consequence of which the noise level of the amplifier output, and consequently of the combined signal, is greatly increased, and, in the case of fading of the carrier when receiving speech modulated signals, the distortion caused by the beat between side bands is unduly magnified.

The second difficulty, like the latter of the two disadvantages already mentioned, arises only in the case of the reception of speech or speech-simulating signals, where the transmission energy is radiated in the form of a carrier and side bands, for relative phase fluctuations in closely adjacent frequencies, such as side band and carrier frequencies, sometimes occur even at one antenna. This causes similar phase fluctuations in the beat of the carrier and side bands, for if of two beating waves one is kept constant in phase, while the other is shifted in phase, their beat is equally shifted in phase. It therefore follows that although the carrier and side band energies experience only radio frequency differences in phase, these differences are transferred to the detected or audio frequency energies, so that it is as impossible to combine the detected energies as it is to directly combine the originally collected radio frequency energies.

The foregoing difficulties may be overcome by automatically switching the receiver to only a single antenna at which fading is not prevalent, and such a system has been disclosed in a co-pending application of John B. Moore, Serial Number 319,768, filed November 16, 1928. The present system is smooth in operation and simple in apparatus, and to a very considerable degree possesses the advantages of the system referred to, for during a great deal of the time all of the antennas except the first are not coupled to the receiver, and except at very rare intervals at least some of the antennas are not coupled to the receiver.

The invention is described more in detail in the following specification, which is accompanied by drawings in which

Figure 1 is a wiring diagram of one form of my invention;

Figure 2 is an arrangement in which the signal energies are combined after rectification; and

Figure 3 is a modification of the arrangement shown in Figure 2.

Referring to Figure 1 it will be seen that there are a plurality of antennas 2, 4, and 6, which, for diversity work, may be given relatively different fading characteristics in any suitable manner, such as by being geographically spaced, or by being positioned in different planes of polarization. The antennas are respectively coupled to an amplifier 8, 10, and 12, the outputs from which are combined at a common transformer 14, the secondary of which is coupled to a common receiver 16, and a common volume control 18. This has been indicated in simple form as comprising a detector 20, in the anode circuit of which there is a battery 22 and a resistance 24 which is grounded at 26 to complete the anode circuit. A condenser 28 is connected in parallel with resistance 24, and the magnitude of this condenser is properly chosen to give the volume control the desired time constant, which, of course, should be made appreciably lower than the rate of signal modulation, whether it be code or speech, in order that the volume control may not attempt to destroy the incoming signals.

The amplifier 8 is suitably biased so that it is always effective to amplify and transmit signal energy collected on the antenna 2. The amplifier 10 is biased with a more negative bias, either entirely or partially by reason of the bias potential obtained across the portion of the resistance 24 lying between ground and the point 30. When the signal volume decreases the current flow through the resistance 24 decreases, in consequence of which the negative bias produced at the point 30 decreases, that is, the bias is made more positive, so that the amplifier 10 is made effective to amplify and transmit energy collected at the antenna 4 to the receiver 16 and the volume control 18.

In a similar manner the amplifier 12 is biased still more negative by the bias lead 34, which is connected to the resistance 24 at the point 36. In this manner the amplifier 12 will be made effective to supply energy to the receiver, should that prove necessary to keep the volume at the desired amount, but only after an attempt has been made to satisfy this requirement, first by antenna 2, and then by antenna 2 supplemented by antenna 4.

Further antennas may be provided, as is indicated by the additional coupling coil 38 of the transformer 14, and the additional bias lead 40.

The arrangement shown directly combines the received radio frequency energies, but in these energies relative fluctuations in phase are apt to occur. This is not so serious a disadvantage in this system as with others, because for the most part antenna 4 will be connected only when fading is prevalent at antenna 2, and so on, in consequence of which there is not likely to be neutralization owing to phase opposition. Also, should be the energies from antennas 2 and 4 oppose one another, for example, then antenna 6 will be connected in circuit because of the action of the volume control 18, so ordinarily a resultant is always available.

In order to avoid the difficulty caused by radio frequency phase fluctuations the energies should preferably be combined after rectification, and a modification illustrating this idea is indicated in Figure 2, in which there are a number of an-

tennas 50, 52, and 54, from which transmission lines 56, 58, and 60 run to radio frequency amplifiers 62, 64, and 66. For the sake of simplicity only one vacuum tube stage has been indicated in these amplifiers, but in practice several stages may be arranged in cascade. The amplified energies are fed to detector tubes 68, 70, and 72, across the output circuits of which filter sections 74 are connected, to bypass the radio frequency components of the detected energies. The anodes of the detector tubes are connected together and to a common source of anode potential 76, in series with which there is a coupling impedance 78, and a volume control impedance 80. In parallel with the volume control impedance a condenser 82 is connected for determining the time constant of the volume control operation. To one terminal of the impedance 80 a plurality of sources of different fixed potentials are connected, which may take the form of a single bias battery 84 provided with different potential taps, and to the various taps on this battery there are connected the leads 86, 88, and 90, which run to the control electrodes of the amplifier tubes. In this manner the amplifiers are biased at graduated values, and these values are so chosen that only the first amplifier is normally conductive, but upon decreased output because of fading at the first antenna the potential drop across the impedance 80 is reduced, which raises the potential at the upper end of the impedance, and thereby raises all of the bias potentials sufficiently to make the amplifier 64 conductive, but not to make the amplifier 66 conductive, except upon still further reduction in the value of the combined energy output. On the other hand the gain in amplifier 62 is automatically decreased should the signal from antenna 50 alone prove too strong, for in this modification all of the amplifiers are volume controlled.

One or more suitable amplifier stages 92 may optionally be coupled to the coupling impedance 78, and any desired form of translating device 94 is coupled to the amplifier.

Instead of a fixed difference in bias a variable difference may be provided, and a modification embodying this feature is indicated in Figure 3, in which there are a number of preferably geographically spaced antennas 102, 104, 106, and 108, each coupled to an amplifier 112, 114, 116, 118, the outputs from which are fed to detectors 122, 124, 126, and 128, respectively. The rectified outputs are connected to a common line 130, and fed to a coupling resistance 132, which is coupled through an amplifier 133 to a translating device 134. The anode potential for the detector tubes is provided from a common source preferably located at 136, as is indicated on the drawings, in order to keep the impedances 132 and 140 at a low potential.

The combined energy is also fed to a volume control resistance 140, in series with the coupling resistance 132. A condenser 142 is connected in parallel with the volume control resistance 140 in order to establish the time constant at which the volume control functions.

As in the arrangement shown in Figure 1, the various amplifiers are biased at different bias values by leads 144, 146, and 148, which are connected to the resistance 140 at suitably chosen different points. If necessary these leads may include sources of fixed potential 154, 156, and 158, the potential values of which are chosen to give the amplifiers the desired initial bias. This arrangement operates like the arrangement

shown in Figure 2 in that the energies from the several antennas, when combined, are combined independently of the phase of the received radio frequency energy. Also an additional bias lead, 143, may be connected from the resistance 5 140 to the amplifier 112, in order to provide volume control for the first antenna, 102. But it is similar to the arrangement shown in Fig. 1 in that the bias values are altered differently, that 10 is, in Fig. 2 the changes caused in the initially different biases are equal, whereas in Fig. 3 the changes of bias are unequal, though the rate of 15 change of bias may be kept equal, for it depends on the rate of flow of current through the resistance 140, and the spacing of the taps on the 20 resistance. With this arrangement all of the amplifiers may be made conductive and equally biased, for little or no signal strength, instead of the first amplifiers receiving an excessive positive bias. Upon increased signal strength the 25 later amplifiers are rapidly cut out in succession by growing graduated negative biases, which increase in geometric ratio.

I claim:

1. The method of controlling the volume of 25 radio signals which includes collecting signal energy on a plurality of antennas, and automatically feeding in response to collected signal energy the collected energy to a receiver from 30 only so many of the antennas as may be necessary to keep the energy supplied to the receiver at a predetermined desirable value.

2. The method of controlling the volume of 35 radio signals which includes collecting signal energy on a plurality of antennas, and effectively automatically coupling in response to collected signal energy the antennas successively to a receiver until an antenna is reached at which fading is not prevalent, so that the energy supplied 40 to the receiver is kept up to a predetermined desirable value.

3. The method of controlling the volume of 45 radio signals which includes collecting signal energy on an antenna, feeding the collected energy to a receiver, collecting signal energy on another antenna, and automatically feeding in response to collected signal energy the latter energy to the receiver only when the energy fed to the receiver from the first antenna falls below 50 a predetermined desirable value.

4. The method of controlling the volume of 55 radio signals which includes collecting signal energy on a plurality of antennas, automatically feeding in response to collected signal energy the collected energy from one of the antennas to a receiver, automatically feeding in response to collected signal energy the collected energy from another of the antennas to the receiver when the aforesaid energy falls below a predetermined desirable value, and automatically feeding in response to collected signal energy the collected energy from another antenna to the receiver when the sum of the aforesaid energies falls below 60 the predetermined desirable value, and so on.

5. The method of reducing fading when receiving high frequency signals which includes simultaneously making a plurality of energy collections of different fading characteristics, and 65 automatically feeding in response to collected signal energy only as many of the collected energies to a common receiver as may be necessary to keep the energy supplied to the receiver at a predetermined desirable value.

6. The method of reducing fading when re-

ceiving high frequency signals which includes collecting signal energy on a plurality of antennas having different fading characteristics, and effectively automatically coupling in response to collected signal energy the antennas successively to a receiver until an antenna is reached at which fading is not prevalent, so that the energy supplied to the receiver is kept up to a predetermined desirable value. 5

7. The method of reducing fading when receiving high frequency signals which includes collecting signal energy on an antenna, feeding the collected energy to a receiver, collecting signal energy on another antenna having different fading characteristics, and automatically feeding in 10 response to collected signal energy the latter energy to the receiver only when the energy fed to the receiver from the first antenna falls below a predetermined desirable value. 15

8. The method of reducing fading when receiving high frequency signals which includes collecting signal energy on a plurality of antennas so relatively positioned that the fading characteristics thereat usually differ, feeding the collected energy from one of the antennas to a receiver, 20 automatically feeding in response to collected signal energy the collected energy from another antenna to the receiver only when fading is prevalent at the aforesaid antenna so that the energy supplied thereby falls below a predetermined desirable value, automatically feeding in response to collected signal energy from another antenna to the receiver only when fading is prevalent at the aforesaid antennas so that the sum of the 25 energies supplied thereby falls below a predetermined desirable value, and so on. 30

9. The method of reception which includes collecting the radiated energy on a plurality of antennas, separately amplifying the collected energies, combining the amplified energies, and 40 controlling the gain in the amplifiers at graduated amounts in response to the combined energy so that more of the amplifiers are made conductive as the volume of the combined energy decreases. 45

10. The method of reception which includes collecting signal energy on a plurality of geographically spaced antennas, separately amplifying the collected energies, separately detecting the amplified energies, combining the detected energies, controlling the gain in the aforesaid step of amplification at graduated amounts in response to the volume of the combined energy, so that more of the amplifiers are made conductive as the volume of the combined energy decreases, and utilizing the combined rectified 50 energy for translation. 55

11. A radio signal volume control system comprising a plurality of antennas for collecting signal energy, a receiver, and biasing means responsive to collected signal energy for effectively 60 coupling only so many of the antennas to the receiver as may be necessary to supply the receiver with a predetermined desirable amount of energy. 65

12. A radio signal volume control system comprising a plurality of antennas for collecting signal energy, a receiver, means coupling each of the antennas to the receiver, and biasing means responsive to collected signal energy for making the coupling means effective in succession until an antenna is reached at which fading is not prevalent, so that the energy supplied to the receiver is kept up to a predetermined desirable value. 70

13. A radio signal volume control system com-

75

- prising a first antenna, a receiver coupled thereto, a second antenna, and automatically biasing means responsive to collected signal energy for controlling the flow of energy from the second antenna to the receiver when the energy from the first antenna falls below a predetermined desirable value.
14. A radio signal volume control system comprising a plurality of antennas, a receiver, means coupling a first antenna to the receiver, biasing means responsive to collected signal energy for allowing the flow of energy from a second antenna to the receiver when the energy from the first antenna falls below a predetermined desirable value, biasing means responsive to collected signal energy for controlling the flow of energy from a third antenna to the receiver when the sum of the energies from the first two antennas falls below the predetermined desirable value, and so on.
15. A radio receiving system for reducing fading comprising a plurality of antennas having different fading characteristics, a receiver, and self acting means responsive to collected signal energy for effectively coupling only so many of the antennas to the receiver as may be necessary to supply the receiver with a predetermined desirable amount of energy.
16. A radio receiving system for reducing fading comprising a plurality of antennas having different fading characteristics, a receiver, means coupling the antennas to the receiver, and self acting means responsive to collected signal energy for making the coupling means effective in succession until an antenna is reached at which fading is not prevalent, so that the energy supplied to the receiver is kept up to a predetermined desirable value.
17. A radio receiving system for reducing fading comprising an antenna, a receiver coupled thereto, a second antenna having fading characteristics different from the first antenna, and self actuating means responsive to collected signal energy for feeding energy from the second antenna to the receiver only when the energy from the first antenna falls below a predetermined desirable value.
18. A radio receiving system for reducing fading comprising a plurality of antennas having different fading characteristics, a receiver, means coupling a first antenna to the receiver, self actuating means responsive to collected signal energy for feeding energy from a second antenna to the receiver only when fading is prevalent at the first antenna so that the energy supplied thereby falls below a predetermined desirable value, self actuating means responsive to collected signal energy for feeding energy from a third antenna to the receiver only when fading is prevalent at the first and second antennas so that the sum of the energies supplied thereby falls below the predetermined desirable value, and so on.
19. A radio receiving system comprising a plurality of antennas, an amplifier for each of said antennas, a common receiver and a common volume control coupled to all of said amplifiers, and means responsive to said volume control for so varying the bias of the amplifiers that more of the amplifiers are made operative as the volume of energy is decreased, in order to keep the total volume at a predetermined desirable value.
20. A radio receiving system comprising a plurality of geographically spaced antennas, an amplifier and a detector for each of said antennas,
- 5 a common receiver and volume control responsive to the outputs of all of said detectors, means responsive to the volume control for so varying the bias of the amplifiers that only so many of the amplifiers are made operative as may prove necessary to keep the sum of the rectified energies at a predetermined desirable value, and means to translate the combined rectified energy.
21. A fading elimination system comprising a plurality of antennae; an amplifier coupled to each antenna; a common combining circuit for combining the outputs of all of said amplifiers; translating means coupled to the common combining circuit; means, independent of said translating means, for rectifying energy from a plurality of said amplifiers; a resistance in series with said rectifying means whereby the rectified energy flows through said resistance; a volume control connection connected between one of said amplifiers and a point on said resistance; and, another volume control connection connected between another one of said amplifiers and a different point on said resistance.
22. In combination a plurality of antennae, an amplifier coupled to each of said antennae, a rectifier for rectifying the energy outputs of a plurality of said amplifiers, a resistance serially connected with said rectifier whereby the rectified energies flow serially through said resistance, and, a plurality of volume control connections connected to different points on said resistance and to a corresponding number of different amplifiers.
23. In combination, a plurality of antennae, a radio frequency amplifier coupled to each of said antennae, a common combining circuit, each of said amplifiers feeding radio frequency energy into said common combining circuit, a detector and radio receiver coupled to said common combining circuit, a rectifier having a resistance serially connected in its output circuit coupled to said combining circuit, and, volume control connections connected from all of said amplifiers but one to different points on said resistance.
24. In combination, a plurality of antennae, a plurality of detectors corresponding in number to said antennae, high frequency circuits separately connecting said antennae to said detectors, a resistance, means for feeding the outputs of a plurality of said detectors through said resistance, and, volume control connections connected from different points along said resistance to different ones of a plurality of said high frequency circuits for varying the outputs of said high frequency circuits in response to the detected outputs in said resistance.
25. In combination, a plurality of antennae, an amplifier coupled to each of said antennae, a detector coupled to each of said amplifiers for detecting the outputs of said amplifiers, a resistance, means for feeding the detected energies serially through said resistance, and, volume control connections connected to different points along said resistance to different ones of said amplifiers.
26. In combination, a plurality of antennae, an amplifier coupled to each of said antennae, a detector coupled to each of said amplifiers, a resistance, means for feeding the outputs of said detectors through said resistance, a source of potential serially connected to said resistance, and volume control connections connected between different points on said source of potential and different ones of said radio frequency amplifiers.

27. In combination, a plurality of antennae, an electric discharge device coupled to each of said antennae to receive waves therefrom, means for producing a control potential which is a function of the amplitude of the wave output from each of said devices, and means responsive to said potential for controlling said devices to render inoperative at least for the transmission of waves of small amplitude those in which the amplitude of the received wave is small compared to that of the received wave in another.

28. In combination, a plurality of antennae so related to each other that the received waves vary differently at the several receivers with variations in transmission conditions that reception conditions vary differently at each, a plurality of electric discharge devices each having an anode, a cathode and a control element, means for supplying the waves received in each of said antennae to a corresponding one of said devices, means for producing a unidirectional electro-motive force having at any instant an amplitude which is a function of the amplitude of the received waves, means for impressing said electro-motive force upon the control electrodes of said devices to so affect the transmission characteristics thereof that those devices which at the instant are receiving waves of substantially lower amplitudes than the waves being received by another device are rendered substantially inoperative for the transmission of waves of said lower amplitudes, and a signal receiving circuit con-

nected to receive waves transmitted by any of said devices.

29. In a signaling system subject to variable transmission conditions, a plurality of receivers each receiving the same signal and so related to each other that the received signals vary differently at the several receivers with variations in transmission conditions, each receiver comprising an electric discharge device, a signal circuit common to said receivers, means for producing a unidirectional potential which is a function of the amplitude of the input to said signal circuit, and means for impressing said unidirectional potential between the electrodes of said electric discharge devices to render inoperative those of said devices in which the amplitude of the received wave is small compared with that of the received wave in another of said devices.

30. In combination, a plurality of radio signal receivers, means for combining the signal output of said receivers, and means for automatically controlling over a continuous range the gain of one of said receivers in response to the amplitude of the signal from said means for combining the signal output of said receivers to render substantially inoperative said one of said receivers when the amplitude of the signal wave received thereby is materially lower than the amplitude of the signal wave received by another of said signal receivers.

HAROLD O. PETERSON.
